W. H. RUTTLE,
BUTTER CUTTER,
APPLICATION FILED FEB. 24, 1920.

Patented Mar. 1, 1921.

Inventor

WILLIAM H. RUTTLE

By *Richard J. Cook*
Attorney

UNITED STATES PATENT OFFICE.

WILLIAM H. RUTTLE, OF SEATTLE, WASHINGTON.

BUTTER-CUTTER.

1,370,158.

Specification of Letters Patent. Patented Mar. 1, 1921.

Application filed February 24, 1920. Serial No. 360,664.

To all whom it may concern:

Be it known that I, WILLIAM H. RUTTLE, a citizen of the United States, and resident of the city of Seattle, county of King, and 5 State of Washington, have invented certain new and useful Improvements in Butter-Cutters, of which the following is a specification.

This invention relates to improvements in 10 butter cutters, and more particularly to devices of that character whereby cakes of butter may be cut into small chips for individual table use.

It is the principal object of the invention 15 to provide a butter cutter of the character above stated, wherein means is provided for cutting chips of different thicknesses, and provision is made for maintaining the cutters taut and securely mounted so as to avoid 20 any unevenness in cutting.

It is also an object of the invention to 25 provide cutters of a novel character which are practically indestructible, together with mounting bars whereby the cutters are spaced to cut thin or relatively thick chips.

In accomplishing these and other objects 30 of the invention, I have provided the improved details of structure, the preferred forms of which are illustrated in the accompanying drawings, wherein—

Figure 1 is a plan view of a butter cutting device embodying the present invention, wherein, for better illustration, one of the pressure levers is shown in lowered position while the other is shown in raised position.

Fig. 2 is a side view of the device, partly 35 in section, showing the parts in the positions as they are illustrated in Fig. 1.

Fig. 3 is an inside face view of a portion 40 of one of the cutter-supporting frame side rails, with the cutter mounting and spacing bar attached thereto.

Fig. 4 is a transverse section taken on the 45 line 4—4 of Fig. 3.

Fig. 5 is a perspective view of one of the cutters.

Referring more in detail to the several figures of the drawing wherein like numerals 50 designate like parts, 1 designates a movable cutter supporting frame, which, in its preferred form of construction, comprises two inwardly facing, channeled side rails 2, which are joined by two opposite end rails 3 to form a substantially rigid frame having 55 a rectangular central opening 4 of such size

that it will receive the ordinary square cake of butter as sold commercially.

The two end rails 3 of the frame are provided with laterally extending wings 5, each 60 of which has a slot 6 therein extending in the central, longitudinal line of the frame and these wings have parallel, vertical flanges 7 formed at opposite sides of the slots between which pressure levers 8 are mounted 65 to turn pivotally in a vertical plane upon pivot pins 9, extending between the paired flanges.

Formed integral with the levers 8 at their inner ends are geared, segmental heads 10, 70 which are adapted to be rotated in mesh with the rack surfaces 11 of standards 12 that are mounted on the opposite ends of a base plate 13, whereon a cake of butter, as indicated at 14 in Fig. 2, may be placed 75 for cutting; the standards being rigidly mounted on the base and extending vertically and slidably through the slots 6 close to the end rails 3 of the frame, and are of such length that cakes of butter of the usual 80 size may be accommodated.

In this construction the base 13 is rectangular, and has a length and width that is slightly less than the length and width of the opening 4, so that the frame may move 85 downwardly about the base.

Extending transversely across the opening 4, at regularly spaced intervals, throughout its length, are the cutters 15, which in their preferred form of construction comprise thin strips of metal having loops 16 formed at their opposite ends which are adapted to receive pins or projections, as shown at 17, extending from bars 18 that are removably attached longitudinally along 95 the inner faces and within the channels of the frame rails 2.

The strips 15 are of such length that they will extend across the opening 4 and the loops 16 will be contained within the channeled portions of the rails 2 and the bars 18, which are secured within the rails by means of screws 19, threaded inwardly therethrough, may be drawn outwardly by the said screws to tension the cutting strips. 105

The bars 18 are each equipped with pins 17 along both the upper and lower edges, with those on one edge spaced at closer intervals than those along the opposite edge, so that, according to the side of the bars on 110 which the cutters are mounted, either thin or relatively thick chips may be cut.

When the device is in use, it is preferred to mount the cutters adjacent the lower edge of the side rails 2, and if it is desired to change the thickness of the chips, the bars 5 are removed and inverted, so that the different thickness may be accomplished but the cutters will still be maintained adjacent the lower edge of the frame. However, if it is desired, the cutters may be mounted to extend across the opening adjacent the top of the frame.

In the present device a wire 20 is attached to the opposite ends of the frame to extend centrally across the frame opening transversely beneath the cutter strips 15 to divide the cakes of butter longitudinally.

Assuming that the device is so constructed, in using the same, a cake of butter to be cut into chips is placed upon the base 20 13 while the frame 1 is in elevated position; or is entirely removed from the base. The frame is then placed in position, in case it had been removed, and the levers 8 swung, from inwardly extending position outwardly, so that the geared heads 10 engaging with the rack surfaces of the standards 12 will move the frame downwardly to press the cutters edgewise through the cake of butter to cut the same in small cakes. The 30 levers are then swung inwardly to raise and release the frame and it can be removed to permit an easy removal of the butter chips from the base.

If it is desired to cut chips of different thickness, the bars 18 are released by loosening the screws 19 and the cutters placed on the opposite sets of pins 17; the bars being inverted if it is desired to maintain the cutters at the lower edge of the frame, and are 40 then attached as before to the rails 2.

What I claim as new, is:

1. A butter cutter comprising a frame having opposite side and end rails forming a rectangular opening for receiving a cake 45 of butter therein, bars secured longitudinally to opposite rails of the frame having pins extending therefrom at spaced intervals and cutter strips extending across said opening having loops at their opposite ends 50 for receiving said pins whereby the said strips are held in cutting position.

2. A butter cutter comprising a frame having opposite side and end rails forming a rectangular opening for receiving a cake 55 of butter therein, bars secured longitudinally to the inner faces of said side rails having pins extending at regularly spaced intervals from opposite edges thereof; the intervals between pins on corresponding 60 edges of the bars being equal but on opposite edges of the bars being different, and cutter strips extended across the opening provided with loops at their opposite ends for receiving said pins to mount the same at

either side of the bars to produce chips of 65 different thicknesses.

3. A butter cutter comprising a frame having inwardly facing, channelled side rails and having a rectangular opening between said rails for receiving a cake of butter 70 therein, bars removably mounted longitudinally within each of the channelled rails having pins projecting from opposite edges thereof with those at corresponding edges spaced regularly at a different interval than 75 those at the opposite edges, cutter strips extending across the opening provided with loops at their opposite ends for receiving the pins at corresponding edges of the bars to space and retain the said strips in cutting position with the loops retained on the pins by flanges of the channelled rails.

4. A butter cutter comprising a base plate whereon a cake of butter may be mounted to be cut into chips, said base having vertical standards at its opposite ends provided with rack surfaces, a frame mounted to move vertically in a horizontal plane on said standards, and having a rectangular opening for receiving the butter cake, levers 85 mounted on the ends of the frame having segmental geared heads thereon adapted to mesh with the rack surfaces of the standards whereby actuation of the levers will 90 actuate the frame toward or from the base, 95 bars secured to opposite sides of the frame having pins extending therefrom at regularly spaced intervals and cutter strips extending across the opening having loops at their ends for receiving said pins whereby 100 the strips are held edgewise in cutting position.

5. A butter cutter comprising a frame having inwardly facing channelled side rails forming a rectangular opening for receiving 105 a cake of butter therein, bars adapted to be mounted within the channelled portions of said rails having pins extending from their upper and lower edges at regularly spaced intervals, with the interval between pins at 110 one side of the bars being different than the interval at the opposite sides, cutter members extending transversely across the opening, comprising thin metal strips turned to engage a butter cake edgewise and having 115 loops at their opposite ends for interchangeably receiving the pins at either side of the said bars according to the thickness of the chips desired, and screws threaded inwardly through the frame rails and into said bars to 120 draw the latter within the channelled portion of the rails to retain the looped ends of the cutters on the said pins and to draw the cutters taut across the opening.

Signed at Seattle, Washington, this 11th 125 day of February, 1920.

WILLIAM H. RUTTLE.
